UNITED STATES PATENT OFFICE

ROBERT UHDE, OF KASSEL-WILHELMSHOHE, GERMANY, ASSIGNOR TO SCHMIDT'SCHE HEISSDAMPF-GESELLSCHAFT MIT BESCHRÄNKTER HAFTUNG, OF KASSEL-WILHELMSHOHE, GERMANY, A CORPORATION OF GERMANY

BOILER GENERATING STEAM ACCORDING TO THE INDIRECT METHOD

Application filed October 27, 1928, Serial No. 315,476, and in Germany November 14, 1927.

My invention relates to steam-boiler installations for the generation of high-pressure steam according to the indirect method in which the working steam-boiler is heated by a heat carrier subjected to the heat of the furnace gases and circulating in a closed system.

In such steam-boiler installations, it has been proposed to utilize the heat in the circulating heat carrier not only for the generation of high-pressure steam but also for heating the feed water for the working boiler.

In known steam boiler installations of this kind, the arrangement is such that the feed-water heater which is heated by the circulating heat carrier is disposed in series with the heating elements in the working boiler. In such a case, the preheating of the feed water is effected by the condensate of the heat-carrying steam after the latter has given up a large part of its heat in generating steam in the heating elements of the working boiler and has thereby been condensed.

In this series arrangement, the heat remaining in the condensate of the heat carrier is not sufficient to heat the feed water for the working steam boiler to the full temperature of evaporation. A part of the heat of the live heating steam must therefore be applied in the first place by way of the heating elements lying in the working steam boiler to bring the preheated feed water to the temperature of evaporation.

In contradistinction to the above, according to my present invention, the feed-water heater is not arranged in series with the heating elements in the working boiler but in parallel therewith, so that both the heating elements in the working boiler and also the heating coils or the like of the feed-water heater are heated by heat-carrier live steam.

As a result of such parallel connection, the heating elements have to transmit to the water in the boiler only the heat of evaporation while the preheating of the feed water up to the full temperature of evaporation is effected by the heating surface provided in the feed heater.

In this way, the maintenance of the outside surface of the boiler heating elements in a

clean condition is considerably facilitated, since impurities that are precipitated at temperature below the temperature of evaporation are thrown down in the container of the feed heater in general in the form of a fine porous mud and do not come into contact with the surface of the heating elements.

A similar protection from deposits is afforded to the heating elements in connection with impurities which are carried over from a first preheating, for example in a flue-gas preheater, in a separated but not precipitated form.

Such deposits can be readily removed from the container of the feed-water heater and its heating coils cleaned by jets of steam or water from the working boiler.

A further advantage of the parallel connection lies in the fact that on account of the smaller heating surface required for the working steam boiler, the thick-walled drum of the latter may be smaller and its cost of production substantially reduced.

In addition, as the preheating of the feed water to the temperature of evaporation is not effected by progressive cooling of the condensate but by condensing live steam of a temperature continuously maintained at a higher point, the mean temperature difference between the heat carrier and the feed water to be heated is correspondingly greater, and thereby also the quantity of heat transmitted, while in particular the co-efficient of heat transmission of the condensing live steam is many times greater than of the cooling liquid condensate.

In the accompanying diagrammatic drawings Fig. 1 shows a longitudinal section through one illustrative form of a steam boiler installation with parallel connection of the heating elements of the working steam boiler and of the feed-water heater according to my present invention. Fig. 2 shows a similar section through a slightly modified form.

In Figure 1, the heat carrier is evaporated in the serpentine or coils, 1, heated by the furnace gases, the steam so generated passing from the intermediate drum, 2, through the pipe, 3, into a group of heating elements, 4, lying in the water space of the working

steam boiler, 5, the condensate from these heating elements flowing through the pipe, 6, into the water collector, 7.

According to the present invention, a part 5 of the live heating steam passes from the pipe, 3, into the heating coils, 8, of the feed-water heater, 9, instead of into the heating elements, 4, in order to heat the feed water for the working steam boiler, 5, to the full 10 evaporating temperature. The condensate from the heating coils, 8, flows through the pipe, 10, back to the water collector, 7.

In the form of the invention shown, the feed water is led from the feed pipe, 11, first 15 into the flue-gas preheater, 12, and thence through the pipe, 14, into the feed-water heater, 9, from which, after being raised to the temperature of evaporation, it passes 20 through the pipe, 15, into the working boiler, 5.

In Figure 2, the path of the live heating steam is the same as in Figure 1, the only difference being that the condensate from the heating coils, 8, as well as that from the heating elements, 4, is led into the common 25 pipe, 16, which is connected to the water collector, 7, of the heat-carrier evaporating system.

The working steam generated passes in a 30 known manner through the pipe, 17, into the superheater, 18, and thence through the pipe, 19, to the engine.

From the pipe, 17, the branch, 20, fitted 35 with a shut-off valve, 21, is led to the container of the feed-water heater, 9, to which is connected in addition the pipe, 22, also fitted with a shut-off valve, 23, so that by means of the branch pipe, any mud that has collected 40 in the feed-heater container can be blown out as required.

In larger boiler units, more than one feed-water heater may be provided while in addition, instead of a single heating coil, a group of heating elements may be arranged 45 in the container of the feed-water heater.

What I claim is:

1. In a steam generator wherein high pressure steam is indirectly generated by means of a heat carrier passing through the heating elements of a working steam boiler and circulating in a closed circuit a portion of which is heated by hot gases, and a feed-water heater having heating elements therein, said feed-water heater heating elements and said heating elements of the working steam boiler being connected in parallel with respect to the heat carrier circuit.

2. In a steam-boiler installation for the generation of high-pressure steam according 50 to the indirect method by means of a heat carrier circulation in a closed circuit and heated by the hot gases in the evaporating system of the closed circuit, in combination a working boiler, heating elements lying in 55 the water space of said boiler, a feed water

heater, heating elements lying in said feed-water heater, a pipe connection between the heat carrier evaporating system and said boiler heating elements, and a pipe connection between the heat carrier evaporating system and said feed-water heating elements, 70 said pipe connections being disposed in parallel.

3. In a steam-boiler installation for the generation of high-pressure steam according 75 to the indirect method by means of a heat carrier circulating in a closed circuit and heated by the hot gases in the evaporating system of the closed circuit, in combination a working boiler, heating elements lying in 80 the water space of said boiler, a feed water heater, heating elements lying in said feed water heater, pipes connecting the upper part of the heat carrier evaporating system with the heating elements in the boiler and in the 85 feed water heater for leading heat-carrier live steam to said heating elements, said pipe connections being disposed in parallel and pipe connections between said heating elements and the lower part of the heat-carrier 90 evaporating system for leading back the condensate of the heat-carrier steam.

4. In a steam-boiler installation for the generation of high-pressure steam according 95 to the indirect method by means of a heat carrier circulating in a closed circuit and heated by the hot gases in the evaporating system of the closed circuit in combination a working boiler, heating elements lying in 100 the water space of said boiler, a feed water heater having a container and heating elements lying in said container, pipe connections between the heat-carrier evaporating system and said heating elements in the boiler and the feed water heater, said pipe connections being disposed in parallel, and a pipe 105 connection between the working boiler and the container of the feed water heater.

5. In combination, a working steam boiler, heating elements lying in the water space of 110 said steam boiler, a feed-water heater, heating elements lying within said heater, a set of water tubes constituting heat absorbing elements, upper and lower headers for said tubes, means for directly connecting one end 115 of the heating elements of the working steam boiler and of the feed-water heater with said upper header, and means for connecting the other ends of said heating elements with said lower header.

6. In a steam generator wherein high pressure steam is indirectly generated by means of a heat carrier passing through the heating elements of a working steam boiler and circulating in a closed circuit a part of which 125 is heated by hot gases, a feed-water heater having heating elements therein, the heating elements of the feed-water heater and of the working steam boiler being connected in parallel with respect to the heat carrier circuit, 130

and means for conducting steam from the working boiler to the top of the water space within the feed-water heater, said feed-water heater being provided with an outlet communicating with the bottom of said water space.

In testimony whereof I have affixed my signature.
